UNITED STATES PATENT OFFICE.

CHARLES H. RIPPL, OF EAST CLEVELAND, OHIO, ASSIGNOR TO THE CLARK CONTROLLER COMPANY, OF CLEVELAND, OHIO, A CORPORATION OF OHIO.

ALTERNATING-CURRENT MAGNET.

Application filed February 26, 1927. Serial No. 171,192.

The present invention relates to the construction of alternating current magnets such as are employed in contactors, circuit breakers and the like, and has for its object 5 the provision of a magnet which is quiet in operation. In the present construction a U-shaped core is employed, the armature being pivotally mounted on one end of the core and so arranged that the pull on the pivot 10 of the armature is at a right angle to the pull on the other or free end of the armature. Another feature of importance is the use of an eccentric bushing for the pivotal armature mounting, thus allowing the meeting 15 faces of the armature and pole to be adjusted to obtain quiet action. To the accomplishment of the foregoing and related ends, said invention, then consists of the means herein-after fully described and particularly point- 20 ed out in the claims.

The annexed drawing and the following description set forth in detail certain mechanism embodying the invention, such disclosed means constituting, however, but one 25 of various mechanical forms in which the principle of the invention may be used.

In said annexed drawing:

Fig. 1 is a side elevational view partly in section showing my improved construction; 30 Fig. 2 is an end elevational view; and Fig. 3 is a perspective view of a detail.

The present magnet is shown as mounted on a panel 1 by means of cap screws 2 which pass through the panel and engage in 35 threaded apertures 3 in the angle plates 4 in which the magnet is mounted by means of pins 5 which pass through the core laminations and the plates and which are secured in position by means of cotter pins 6.

The magnet core 10 is U-shaped and is made up of laminated sheets as in the usual A. C. magnet construction and the legs 11 and 12 of the U are horizontal with the bottom of the U in the vertical position against 45 the panel, thus leaving an open front to the magnet which is closed by a pivotally mounted laminated armature 14. Mounted on the upper leg 11 of the core is the magnet winding 15 as well as a shading coil 16 which is 50 formed by a yoked strap member 17 and a cross rod 18 mounted in a slot in the end face of the leg 11. This strap member 17 has a forwardly extending tongue 19 terminating in a down turned end 20 which is 55 provided with an aperture passing over a

bolt 21 and held in place by a nut 22 on the end of the bolt.

The lower leg of the core is formed with a substantially cylindrical end 25 which is apertured to receive a bushing 26, the ends 60 of which are turned over to clamp the laminated core pieces together. Mounted in this bushing is a pivot pin 27. The armature 14 is formed of a series of thin plates or laminations 28 which are secured between two 65 arms 29 which are of less width than the plates thus allowing the plates to extend slightly beyond the arms to form the meeting face 30 for engagement with the end pole face 31 of leg 11. The plates 28 are 70 curved at their lower ends to fit around the curved end of the lower leg 12 of the core. The lower ends 32 of the armature arms are split as at 33 and are provided with cap screws 34. These lower ends are apertured 75 to receive eccentric bushings 35 which are held in adjusted position by tightening the cap screws 34. This adjustable bushing allows the armature to be adjusted sufficiently to bring the meeting face 30 thereof 80 into perfect alignment with the face of the upper leg. The open position of the armature is shown in dotted lines in Fig. 1 and the downwardly extending end 20 of the strap member 17 acts as a stop for the armature 85 as shown, the meeting face 40 of the armature being beveled off to rest against the strap end.

In the present construction only two meeting surfaces are employed, the face 30 of the 90 armature and the end 31 of the leg 11 and thus these two surfaces are the only parts which must be machined or finished. This portion 30 is surfaced off below the level of the rest of the armature thus forming a 95 shoulder 37 which is below the bottom of the end 31 of the pole. The curved surface 25 on the core and armature ends 28 are spaced apart so as to form a curved gap 41 to prevent sticking.

The final adjustment of the eccentric bushings 35 is made while the magnet is in 105 operation and the armature position is changed to obtain the quietest possible operation of the unit. The pull of the upper pole 105 face 31 is in a horizontal direction when the magnet is mounted as shown while the pull through the bottom leg 12 against the armature is downwardly in a vertical direction, that is, the pulls of the two legs of the core 110

on the armature are always at right angles to each other, thus reducing the tendency of the armature to rattle to a minimum.

Other modes of applying the principle 5 of my invention may be employed instead of the one explained, change being made as regards the mechanism herein disclosed, provided the means stated by any of the following claims or the equivalent of such stated 10 means be employed.

I therefore particularly point out and distinctly claim as my invention:

1. In A. C. magnet construction the combination of a U-shaped core provided with 15 the magnet winding and having a curved end on one leg, and a faced end on the other leg, an armature having a curved end pivotally mounted about said first named leg to provide a curved air gap, said armature 20 having a faced portion adapted to be drawn against said other leg, the pull through said faced surfaces of said core leg and armature being substantially at right angles to the pull between said armature and other leg at the 25 pivotal connection and adjusting means at such pivotal connection to allow said two abutting faces to be brought into alignment.

2. In A. C. magnet construction the combination of a U-shaped core provided with 30 the magnet winding and having a curved end on one leg, and a faced end on the other leg, an armature having a curved end pivotally mounted about said first named leg to provide a curved air gap, said armature having 35 a faced portion adapted to be drawn against said other leg, said armature having two arms forming a yoke around said curved leg end, a pivot pin mounted in said leg, and adjustable eccentric bushings mounted in 40 said two arms and adapted to receive the ends of said pin to provide an adjustable mounting for said armature.

3. In A. C. magnet construction the combination of a U-shaped core having the mag- 45 net winding on one leg and having the end

of such leg faced, the other leg of said core having a bushed aperture, a pivot pin mounted in said aperture, an armature consisting of two arms having these lower ends apertured, and a laminated armature member mounted between said arms and having a faced portion adapted to abut against said faced leg end, eccentric bushings adjustably mounted in said arm apertures and adapted to receive said pivot pin to pivotally mount 50 said armature, said bushings being movable to bring said faced portion of said armature into correct alignment with said faced leg end.

4. In A. C. magnet construction the combination of a U-shaped laminated core having a pivotal mounting at the end of one leg and a faced end on the other leg, and provided with a magnet winding, a laminated armature pivotally mounted on said 60 first-named leg and having a faced portion adapted to abut against said faced portion of the other leg to obtain a magnetic pull at right angles to said abutting faces, the pivotal mounting on said armature and said 65 first-named leg being such as to obtain a magnetic pull longitudinally of said armature and at a right angle to the pull through said abutting faces.

5. In A. C. magnet construction the combination of a U-shaped laminated core provided with a magnet winding having a curved end on one leg, and a faced end on the other leg, a laminated armature having a curved end pivotally mounted about said 75 first-named leg to provide a curved air gap, and to obtain a magnetic pull longitudinally of said armature, said armature having a faced portion adapted to be drawn against said faced end of said other leg to obtain a 80 magnetic pull at right angles to said abutting faces and at right angles to the pull through said armature.

Signed by me this 18th day of Feb., 1927.

CHARLES H. RIPPL.
